UNITED STATES PATENT OFFICE.

GUSTAVE VOGT, OF LIMOGES, FRANCE.

DESIGN FOR A DISH-COVER.

SPECIFICATION forming part of Design No. 15,122, dated July 1, 1884.

Application filed January 30, 1884. Term of patent 7 years.

To all whom it may concern:

Be it known that I, GUSTAVE VOGT, of Limoges, in the Republic of France, have invented a new and original Design for Dish-Covers, of which the following is a full, clear, and exact description, reference being had to the accompanying drawings, making part of this specification, in which—

Figure 1 is a side elevation of a dish with a cover made according to my design, and Fig. 2 is an end elevation of the same.

Similar letters of reference indicate corresponding parts.

This design relates to covers for tureens and other dishes belonging to dinner-sets; and it consists of a dish-cover the handle of which forms a continuous curve, or nearly so, with the longitudinal outline of the cover.

A in the drawings represents the body of a tureen or other dish, which is made of oval, rectangular, or other shape. B is the cover, which corresponds in shape to that of the body. C is the handle of the same. The handle C is made of a flat curve, which forms a continuation, or nearly so, of the upwardly-swelling longitudinal outline of the cover, as shown clearly in Fig. 1. The ends of the handle C are enlarged and suitably ornamented at their point of connection with the cover. The lateral swell of the cover corresponds to the lon-

gitudinal swell and connects abruptly with a depressed portion below the handle C, whereby sufficient space is provided for placing the fingers below the handle. This depression is required, so as to give the desired continuity 35 between the outlines of the cover and handle.

I am aware that covers with depressions below the handles are not new, and I therefore do not claim this feature.

I am also aware that dish-covers having a 40 raised or convex portion bulging out above the lower part of the cover up to nearly a level with the handle have been used heretofore, which is, however, different from my design, in which the handle forms a direct continuation 45 of the convex cover without any intermediate convex portion.

Having thus described my invention, I claim as new and desire to secure by Letters Patent—

The design for a dish-cover, composed of a 50 slightly-swelling cover and of a handle that forms a continuation of the slightly-swelling outline of the cover, as shown and described.

In testimony that I claim the foregoing as my invention I have signed it this 5th day of November, 1883.

GUSTAVE VOGT.
